UNITED STATES PATENT OFFICE.

CLOYD E. BURNS, OF JACKSON HEIGHTS, NEW YORK, ASSIGNOR TO REMINGTON TYPE-WRITER COMPANY, OF ILION, NEW YORK, A CORPORATION OF NEW YORK.

TYPEWRITING MACHINE.

Application filed July 13, 1926. Serial No. 122,239.

My invention relates to typewriting and like machines and more particularly paper end stop devices to aid in accurately positioning work sheets into the machine.

5 The main object of the invention, generally stated, is to provide simple and efficient devices of the character specified.

A further object of the invention is to provide simple and efficient means by which end 10 stops may be adjusted in a curved path around a cylindrical platen.

15 A still further object of my invention is to provide means whereby certain of said stop devices may, at will, be shifted into or out of effective position and maintained indefinitely in either of said positions.

20 To the above and other ends which will hereinafter appear, my invention consists in the features of construction, arrangements of parts and combinations of devices set forth in the following description and particularly pointed out in the appended claims.

25 In the accompanying drawings, wherein like reference characters designate corresponding parts in the different views:—

Fig. 1 is a fragmentary, central, fore and aft, vertical sectional view showing a part of a typewriting machine equipped with the devices of my invention.

30 Fig. 2 is a like view of the same showing the end stops 46 in use.

Fig. 3 is a transverse sectional view of the construction taken on the line 3—3 of Fig. 2 and looking in the direction of the arrows 35 at said line.

Fig. 4 is a detail perspective of the combined paper table and deflectors together with the end stop devices carried thereby.

40 Fig. 5 is a top plan view of a carriage equipped with the devices of my invention and showing more or less diagrammatically the paper feed rollers, etc.

Fig. 6 is a fore and aft, vertical, sectional view showing a modified form of end stop 45 and means for supporting and adjusting it.

Fig. 7 is a detail perspective view of one of the end stops shown in Fig. 6.

I have shown my invention, in the present instance, embodied in a #23 Remington 50 bookkeeping machine and used in combination with features disclosed in the application of Frederick A. Hart, Serial No. 120, 408, filed July 3, 1926 and disclosed also in the joint application of Sigurd L. Walsoe 55 and John P. Hill, Serial No. 121,134, filed

July 8, 1926. While from certain aspects of the present invention, features thereof are claimed in combination with other features invented by the said Frederick A. Hart and disclosed and claimed in his said application, nevertheless, from other aspects of my invention, the paper end stops, etc., are of general application and may be employed in various characters of typewriting and like machines, all as will hereinafter more clearly 65 appear.

In the accompanying drawings, I have shown only so much of the #23 Remington bookkeeping machine, and the constructions disclosed in said Hart and Walsoe & Hill applications, as is necessary to arrive at an 70 understanding of the present invention in its embodiment therein.

Generally stated, the machines of said applications are employed in various kinds of 75 billing operations, where two or more work sheets are to be correlated in the machine and printed at a single operation. However, I do not deem it necessary to describe specifically the many different forms of billing 80 operations in which the said machines may be used. It is sufficient for an understanding of the present invention to describe in general terms one mode of billing that may be successfully carried out with the aid of 85 said machines and perhaps briefly refer to some of the various other methods in connection with which the machines may be employed together with the paper end stop devices of my invention.

90 One method of using the machine which will be specifically referred to, is its employment, for example, by a public service corporation such as, say an electric or gas light company, for simultaneously, or at one writing, making out a bill, making corresponding entries on the ledger sheet carrying the account, and on a record or register sheet which receives the entries written on all of the individual bill and ledger sheets. In the example referred to the register sheet and its accompanying carbon sheet remain in the machine. The ledger sheet which usually requires but a single cross line entry at a time, say, for the month for which the entry is made, may be in the nature of a blank with different vertically ruled columns to be filled in under appropriate printed headings; each cross line of the sheet being ruled off 95 horizontally and given over to a different month, 100

and the entire sheet covering a period of anywhere from, say, eighteen to thirty-six months. Means are provided to enable each ledger sheet to be quickly introduced back-
wardly from in front of the platen and properly positioned to receive the requisite entries in the line allotted for the month in question without disturbing the previously introduced register sheet. Means also are provided for then quickly entering a bill sheet and accompanying carbon sheet rearwardly into the machine from in front of the platen, and accurately positioning them in proper correlation with the previously introduced ledger sheet and the printing line. The entries may then be made on the bill sheet and these will be transferred through interposed carbon sheets to the ledger and register sheets. If desired, additional entries may be made on the ledger sheet which are not to appear on the bill or register sheet. The bill and ledger sheets and accompanying carbon sheet are then rapidly withdrawn from the machine without disturbing the register sheet, and another ledger sheet and a bill sheet with accompanying carbon sheet may then be quickly introduced as before, and so on.

In the example of the billing operations explained above the end stops of my present invention are intended to coact with the ledger sheet, to quickly and accurately effect a positioning thereof under varying conditions. It should be understood, however, that in other uses of the machine, the said stop devices of my invention will coact with other sheets in a variety of ways, some of which will be hereinafter explained.

With the foregoing general explanation, I will now proceed to briefly describe so much of the said Hart machine as is necessary to arrive at an understanding of my invention in its embodiment therein.

The frame of the machine is of the usual construction and includes a top plate 1 carrying fixed guide rails 2, oppositely grooved to receive crossed anti-friction guide rollers 3. These rollers are also received in oppositely grooved carriage rails 4 at the front and rear of the carriage, said rails being connected with the end bars 5 and 6 of the carriage.

The carriage, which is power driven in the usual manner, is thus supported and mounted to travel from side to side of the machine over the top plate under control of the usual escapement mechanism (not shown), and in some instances under control of the usual tabulator mechanism.

The platen 7 is carried by the platen frame in the usual manner, said platen frame comprising end plates 8 and 9 united by suitable cross bars. The platen frame is connected to the carriage or truck by links 10 in the usual manner, which links ordinarily guide the

platen frame in its case shifting movements. The present machine, however, is intended to write only with capital letters or upper case characters and there is, therefore, no case shifting movements of the platen and platen frame; the platen frame being firmly held in its upper case position on the carriage, where it will coact with the outermost types 11 on the type bars 12. These type bars are mounted in a type bar segment in the usual manner to swing upwardly and rearwardly to printing position where they strike against the front face of the platen.

The usual ribbon vibrator mechanism is employed so as to interpose the ribbon in the path of the types 11 at each actuation of a type bar. Only the upper end portion of the ribbon vibrator 13 is shown, it being understood, however, that the vibrator is guided for up and down movement on the type guide 14 in the usual manner.

As in the construction disclosed in said Hart application, there are two curved paper deflectors 15 and 16 employed beneath the platen, one arranged above the other and maintained spaced apart by intermediate spacing members or blocks 17 and 18 located near the ends thereof, as best shown in Fig. 4. Generally speaking, these deflectors beneath the platen conform substantially to the curvature of the latter, or are substantially concentric therewith, and extend substantially throughout the length of the platen. As thus constructed there are two separate channels provided, one of which is the open channel 19 between the two deflectors, and which is bounded at its ends by the spacing members 17 and 18, either or both of which may constitute side edge guides or gages for cooperation with one or both side edges of a work sheet or sheets introduced into the channel 19. The other separated channel 20 is provided between the under surface of the platen and the upper deflector 15. It will be seen that the forward edge of the deflector 16 terminates in advance of the forward edge of the deflector 15. The deflector 16 is continued up at the rear to form an upwardly and rearwardly extending paper table 21, which terminates at a considerable height above the platen. On the other hand, the deflector 15 terminates in the rear of the platen at a much lower point and below the top of the platen, where it is bent to form a loop 22 that loosely surrounds a rod 23 fixedly connected at its ends to the end plates 8 and 9 of the platen frame. In this manner the rigidly united deflectors 15 and 16, together with all of the parts carried thereby,

are mounted on the rod 23 and have a slight pivotal movement on said rod. The construction is such that the heavier parts connected to the paper deflectors in the rear pivot rod 23 cause the forward edge portion of the deflector 15, normally, to be lightly pressed

against the platen, or against the interposed sheets R, R'. In this manner the sheets R, R', are held snugly against the platen and sheets I, L, L' intended to be introduced 5 rearwardly into the channel 19 are prevented from entering the channel 20. By moving the upper end of the paper table forward, the forward end portions of the deflectors may be moved downward a limited 10 distance, thus carrying the forward contact edge of the deflector 15 away from the platen.

In order to facilitate the backward introduction of work sheets into the channel 19 15 from in front of the platen there is provided in accordance with the Hart invention, a guide, shield or paper deflector 24 that is movable on the carriage from a substantially horizontally disposed ineffective position, 20 shown in dotted lines in Fig. 1, to a downwardly and rearwardly inclined effective position, shown in full lines in said figure and vice versa.

The deflector 24 has depending arms 25 at 25 the ends thereof, each of said arms being pivoted at 26 on an end plate 8 or 9 of the platen frame. In this manner the deflector 24 is mounted for pivotal movement from the ineffective dotted line position, shown in 30 Fig. 1, where it is out of the paths of the types, to the full line position where it crosses the printing line and extends in the path of the types. In this last mentioned position the deflector overlaps the forward 35 edge of the deflector 16 and forms virtually a continuation of the channel 19 to aid in quickly and effectively introducing work sheets backwardly beneath the platen into the channel 19.

It is unnecessary, for the purpose of the present invention, to disclose the means by which this deflector 24 is actuated and by which the fine wire line indicator 27 is automatically shifted from the effective, dotted-line, to the ineffective full-line position in 45 Fig. 1, when the deflector 24 is shifted from the dotted to the full-line position and vice versa. It also is unnecessary to disclose herein the means by which these devices are 50 automatically controlled by a shifting of certain of the feed rollers 28 and 29 from the ineffective position shown in Fig. 1 into contact with the platen or a work sheet thereon as shown in Fig. 5. Nor is it necessary to disclose the means for automatically lowering the ribbon vibrator from the full to the dotted-line position in Fig. 1 when the deflector 24 is moved from ineffective to effective position, thus giving ample clearance 55 between said deflector and vibrator. All of such means are fully disclosed in said hereinbefore mentioned applications.

It will suffice for the purpose of arriving 60 at a better understanding of this invention, in its present embodiment, to bear in mind

that the parts referred to operate in the general manner indicated above.

As disclosed in said previously filed applications a set of feed rollers 30 coact only with the work sheet R and its carbon sheet R', whereas one or more additional sets of feed rollers 28 and 29 are employed depending on the use of the machine as a so-called "two-sheet" biller, or for more than two work sheets. The specific manner of mounting these feed rollers for shifting movement into and out of cooperation with the work sheets with which they coact has been fully explained in the applications hereinbefore referred to and need not be specifically described herein.

In accordance with the present invention certain adjustable work sheet gaging means, or paper end stops, which coact with the bottom edge of a ledger sheet L introduced 85 through the channel 19 are supported on the paper table and contribute to the preponderance of weight back of the pivot rod 23, spoken of above. These devices of the present invention and the manner of mounting 90 and adjusting them will now be described.

Upright bars 31 are fixed at 32 to the back of the paper table 21 and extend upward beyond the upper end of the table through openings 33 (Fig. 4) in the upper 95 bent portion thereof. These bars are connected at their upper ends to a cross bar 34 by suitable connecting means. Such connecting means, in the present instance, comprise headed bolts 35 and nuts 36. Each associated pair of bolts 35 also pass through openings in a downwardly extending, inclined bar 37 to firmly connect the latter to, and support it wholly at its upper end by, the associated bar 31 and cross bar 34. Each 100 bar 37 overlies its associated bar 31, and is spaced apart therefrom to form an intervening channel 38. Each channel 38 is bounded on the rear side by the paper table 21 and a bar 31, and on the forward side by the overlying bar 37. Each channel 38 at its lower 105 end communicates with the channel 19 intermediate the deflectors 15 and 16. It will be seen that the lower unsupported end of each bar 31 passes down and is bent forward 110 behind the pivot rod 23, and terminates in a bevel face 39 on its rear side where it enters the channel 19. This is to insure a sheet introduced into the channel 19 from the front of the platen, passing from the channel 19 up through the channels 38 between the parallel bars 31 and 37 until arrested by an end stop 40 in the path thereof.

The end stop 40, in the present instance, is formed as a flange extending at right angles 115 to the plane of a sheet metal bar 41 which extends between the upright bars 37 and is formed at its ends with guide loops 42, (see Fig. 3) which surround the bars 37. The stop bar 41 is thus mounted for up and 120

down adjustment on the bars 37 and may be retained in any position to which it is thus adjusted by set screws 43. Each screw is received in a tapped opening in the associate loop 42 and bears at its inner end against the forward face of the bar 37 received in said loop. It will be seen that the stop face or flange 40 extends in the path of the bottom edge of each ledger or other work sheet L guided rearwardly and upwardly through the channels 19 and 38 and effectively arrests said sheet.

When the lower edge portion of each ledger sheet L is to be brought to the printing line, in order to write at and near the bottom of the sheet, the range of adjustment of the bar 41 is insufficient to bring the stop 40 to a position where it will coat with the bottom edge of the sheet. Therefore, other end stops have been provided which will now be described.

It will be seen that two thin flexible or resilient metal arms 44 are pivoted at 45 on the front face of the bar 41. The pivotal mounting of these arms provides sufficient friction to hold the arms in either of the two positions to which they may be swung around their pivots, i. e., either to the ineffective position, shown in Figs. 1, 4 and 5, where the arms overlie the bar 41, or to the effective position, shown in Figs. 2 and 3, where they extend down at substantially right angles to said bar 41. The free end of each arm is bent at right angles to the body portion thereof to form an end stop 46 against which the bottom edge of a ledger sheet L is adapted to abut when the arms are in effective position. From an inspection of Fig. 2, it will be seen that by reason of the flexible character of the arms 44 they may be bent around the cylindrical platen and conform to the general contour of the deflectors 15 and 16, so that the stops 46 may be adjusted around the platen in the channel 19 by an adjustment of the bar 41 in its lower positions along the bars 37. In this manner the stops 46 may be brought into use to coat with the bottom edge of a work sheet L when said edge is within the channel 19 and beyond the range of the stop 40, as shown in Fig. 2.

In the present example, assume that the ledger sheets L are in the nature of printed blanks with separate spaces for various entries thereon, some at least of which are written thereon through an interposed carbon sheet L', or in some instances each bill sheet I may have a carbonized back which would answer the same purpose. Also assume that each ledger sheet has printed thereon the months of the year, or the months of more than one year. If, for example, the entries are to be made near the top of each ledger sheet in an appropriate cross line for the month of, say, January, then the opera-

tion will be as follows. The first ledger L is introduced rearwardly, as previously described, and accurately positioned with reference to a line finder or indicator 27. When this position has been attained the end stop 40 is adjusted to coat with the bottom edge of the ledger sheet L, as shown in Fig. 1, and all successive ledger sheets adjusted to said end stop 40 will be accurately positioned to receive the "January" entries. When entries are to be made for the next month, "February", the first sheet will be positioned with the aid of the line indicator 27 and the stop 40 is adjusted as previously described, and all successively introduced ledger sheets L may be quickly and accurately introduced to properly receive entries for that month, and so on for succeeding months.

As entries reach the lower end portion of each ledger sheet L, the lower end thereof is within the channel 19 when properly positioned to receive such entries, and each of such sheets is therefore out of the range of adjustment of the end stop 40. At this time the arms 44 may be swung down into position at right angles to the bar 41, thus bringing the end stops 46 into effective position in advance of the end stop 40. An adjustment of the bar 41 towards or away from the platen is effective at this time to adjust the end stops 46 along the channel 19 and in a curved path around the platen, as shown in Fig. 2, until the stops coat with the bottom edge of the first ledger sheet previously positioned with the aid of the line indicator 27.

In this manner entries may be made at as low a point on each ledger sheet as is required, it being understood that a single adjustment of the stops 46 suffices for entering bills during a given month and that the stops 46 operate in the same general manner, and for the same purpose as the end stop 40, but are brought into use when the stop 40 is no longer available to coat with a ledger sheet.

I have hereinbefore indicated that the present machine is capable of a very wide range of use, and may be employed with or without slight change in almost any character of billing or like work wherein two or more sheets are employed, and where one or more work sheets are introduced into and removed from the machine, while another or other sheets are retained in the machine and a certain correlation is required between the sheet or sheets retained in the machine and those introduced therein from time to time. Therefore the end stops may be employed in a variety of ways.

For example, let it be supposed that the machine is to be used as a check writing machine, in which a copy is to be made of all checks as they are written. In this event the checks only would be rearwardly introduced

into the channel 19, the end stops 46 being advanced to some such position as that indicated in Fig. 2 and permitted to remain in such position indefinitely. The record of the checks written would be manifolded through the carbon sheet R' to the record sheet R, both of which latter sheets are fed through the separate channel 20. In this event the sheet R would constitute a "pay roll" or "register" sheet, the use of the stops 46 in check-writing providing for the adjustment of such stops to accord with checks of different depths.

Generally speaking, the sheet R, if used in book-keeping work with a ledger sheet, may constitute a so-called "register" or "proof sheet." If used when copying invoices, it may constitute a "sales sheet" or a "distributing sheet." If used in check-writing it may constitute a "payroll" or "register sheet." In each event, however, the sheets R and R' remain in the machine while the remaining work sheets I and L (or either of them as the case may be) are removed after each writing, and new sheets entered in place thereof with the aid of the stop devices of my invention.

In some instances the stops corresponding to the stops 46 may be used without the stop 40 or the bar 41. Thus, in the modified form of construction shown in Figs. 6 and 7 an end stop is provided at the lower end of a flexible arm 48. This arm is looped at the upper end, as indicated at 49, and provided with a second depending arm 50 which terminates in a contact projection 51. This construction is such that the flexible arm 48 is formed integral with its own carrier and may straddle over the upper edge 40 of the paper table 52, the arm 48 extending down in front of the table and the arm 50 extending down in the rear thereof. The contact projection 51 bears against the rear face of the paper table and with the frictional resistance of the arm 48 against the deflector 16 holds the stop device in the position to which it may be adjusted. It will be understood that this construction enables each stop 47 to be adjusted not only around the platen in the channel 19 but also longitudinally of the platen. As many of these stop devices may be employed, as desired, two such devices, however, being usually sufficient.

Various changes may be made without departing from my invention as it is defined in the accompanying claims and certain features thereof may be employed without others.

What I claim as new and desire to secure by Letters Patent, is:—

1. In a typewriting or like machine, the combination of a carriage, a platen carried thereby, two curved paper deflectors arranged one above the other and extending

beneath the platen, means for maintaining said deflectors spaced apart so that they with the platen will form two separated channels through which work sheets may pass, one of said channels being between the platen and the upper deflector, the other channel being between the two deflectors, a third paper deflector carried by the carriage in front of the platen and shiftable from an ineffective position out of the path of the types and where it will direct a work sheet introduced rearwardly past the printing line to the channel between said curved deflectors, a stop with which the bottom edge of a work sheet in the channel between the upper and lower curved deflectors coacts to position said work sheet, and means for affording an adjustment of said stop in the general direction of the line feed of a work sheet.

2. In a typewriting or like machine, the combination of a cylindrical platen, a bar adjustable towards and from the platen, a flexible arm carried thereby, and a paper end stop carried by said arm, the flexibility of the arm enabling it to conform generally to the curvature of the platen and to bend around it in the adjustment of said bar towards and from the platen.

3. In a typewriting or like machine, the combination of a cylindrical platen, a bar adjustable towards and from the platen, a flexible arm mounted thereon for movement into and out of a position for use, and a paper end stop carried by said arm and shiftable with it into and out of a position for use, the flexibility of said arm enabling it to bend around the platen in the adjustment of said bar and enabling the stop to be adjusted in a circular path around the platen.

4. In a typewriting or like machine, the combination of a cylindrical platen, a bar adjustable towards and from the platen, a paper end stop carried by said bar, a flexible arm carried by said bar, and a second paper end stop carried by said arm and adjustable around the platen in a curved path due to the flexibility of said arm by an adjustment of said bar, whereby the end stop on the arm may reach around the platen to a point where the end stop on said bar could not be adjusted to coact with an edge of a work sheet.

5. In a typewriting or like machine, the combination of a cylindrical platen, a bar adjustable towards and from the platen, a paper end stop carried by said bar, a flexible arm carried by and adjustable with said bar, a second paper end stop carried by said arm and adjustable therewith around the platen in a curved path due to the flexibility of said arm, whereby the end stop on the arm may reach around the platen to a point where the end stop on said bar

could not be adjusted to coact with an edge of a work sheet, and a pivotal connection between said arm and bar that enables the arm to be moved from an ineffective position 5 substantially parallel with the bar to an effective position extending substantially at right angles thereto.

6. In a typewriting or like machine, the combination of a platen, a paper end stop, 10 an adjustable carrier therefor, and a second paper end stop adjustable on said carrier to operate in advance of said first mentioned stop.

7. In a typewriting or like machine, the combination of a platen, a paper end stop, 15 a carrier therefor adjustable in the direction of the line feed of the paper, a second paper stop, and means by which said second stop is shiftably mounted on said carrier for movement from an ineffective position to an effective position where it operates in advance of said first mentioned stop.

8. In a typewriting or like machine, the combination of a platen, parallel guide surfaces 20 between which a work sheet is received and by which it is guided, a cross bar extending between and supported on certain of said guide surfaces for adjustment in the direction of the line feed of the 25 paper, and a paper end stop on said cross bar to coact with the work sheet received between said parallel guide surfaces.

9. In a typewriting or like machine, the combination of a platen, parallel guide surfaces 30 forming channels in which a work sheet may be received when introduced rearwardly from the front of and beneath the platen, said channels being open at the lower ends and closed at the upper ends, 35 and a paper end stop adjustable in the direction of the line feed of a work sheet and which coacts with the bottom edge of a work sheet introduced from the front of the platen 40 through said channels.

45 10. In a typewriting or like machine, the combination of a platen, a paper deflector between which and the platen is provided a channel to receive work sheets introduced from the rear of the platen, a second paper deflector below said first mentioned deflector 50 and with it forming a second separate channel through which a work sheet is introduced from in front of and beneath the platen, parallel guide surfaces in the rear 55 of the platen and which form channels that constitute a continuation of said second channel and in which a work sheet introduced backwardly through said second channel may pass, and a paper end stop adjustable 60 in the direction of the line feed of a work sheet and cooperative with the bottom edge of a work sheet introduced through said second channel.

65 11. In a typewriting or like machine, the combination of a platen, a paper deflector

between which and the platen is provided a channel to receive work sheets introduced from the rear of the platen, a second paper deflector below said first mentioned deflector and with it forming a second separate channel 70 through which a work sheet is introduced from in front of and beneath the platen, parallel guide surfaces in the rear of the platen and which form channels that constitute a continuation of said second channel 75 and in which a work sheet introduced backwardly through said second channel may pass, a paper end stop adjustable in the direction of the line feed of a work sheet and cooperative with the bottom edge of a work sheet introduced through said second channel 80 and a flexible arm which carries said end stop and a bodily adjustment of which arm effects a corresponding adjustment of the stop, the flexibility of said arm enabling it 85 to bend around the platen and thus adjust the end stop in a curved path around the platen.

12. In a typewriting or like machine, the combination of a cylindrical platen, an end 90 stop for the paper, means for guiding the end stop in a curved path around the platen and means for adjusting said stop along said curved path, said adjusting means including a flexible arm by which the stop is 95 carried, the flexibility of the arm enabling it to bend and conform to the curved path along which the stop may be adjusted.

13. In a typewriting or like machine, the combination of a cylindrical platen, guide 100 surfaces forming an open channel through which work sheets may be introduced rearwardly from in front of the platen, such guide surfaces directing the sheet thus introduced from beneath upwardly and in the 105 rear of the platen, and a paper end stop located in said channel and adjustable therein in a line feed direction.

14. In a typewriting or like machine, the combination of a cylindrical platen, an end 110 stop for the paper, a flexible arm which carries said stop, the flexibility of the arm enabling it to be bent to a curved condition which conforms generally to the curvature of the platen, and means for thus bending 115 said arm.

15. In a typewriting or like machine, the combination of a cylindrical platen, an end 120 stop for the paper, a flexible arm which carries said stop, the flexibility of the arm enabling it to be bent to a curved condition which conforms generally to the curvature of the platen, means for thus bending said arm, and means which enable said arm and the stop carried thereby to be swung to and 125 maintained indefinitely in an ineffective position.

16. In a typewriting or like machine, the combination of a cylindrical platen, a plurality 130 of end stops, a plurality of flexible

arms each of which carries an end stop, the flexibility of the arms enabling them to conform generally to the curvature of the platen, and means for guiding said arms in a curved path around the platen.

17. In a typewriting or like machine, the combination of a cylindrical platen, a plurality of end stops, a plurality of flexible arms each of which carries an end stop, the flexibility of said arms enabling them to be bent in a curved condition around the platen, means for thus bending said arms, and means for pivotally connecting each of said arms to its support, whereby each of the arms with the stop carried thereby may be swung to positions at substantially right angles to each other into and out of effective position.

18. In a typewriting or like machine, the combination of a cylindrical platen, an end stop, a flexible arm which carries said end stop, the flexibility of said arm enabling it to conform generally to the curvature of the

platen, means for guiding said arm in a curved path around the platen, and means for affording a bodily adjustment of said arm together with the end stop in order to set and maintain the stop in different selected positions of use.

19. In a typewriting or like machine, the combination of a cylindrical platen, an end stop for the paper, a flexible arm which carries said stop, the flexibility of said arm enabling it to be bent to a curved condition which conforms generally to the curvature of the platen, means for thus bending said arm, and a pivot on which said arm is mounted for pivotal movement from an ineffective position substantially parallel with the axis of the platen to an effective position around the platen.

Signed at New York, in the county of New York, and State of New York, this 12th day of July, A. D. 1926.

CLOYD E. BURNS.
